C Colby.
Lock for Fruit-Boxes.

N° 75372

Patented Mar 10, 1868.

United States Patent Office.

CHARLES COLBY, OF MADISON, WISCONSIN.

Letters Patent No. 75,372, dated March 10, 1868; antedated September 10, 1867.

IMPROVEMENT IN LOCK FOR FRUIT-BOXES, &c.

The Schedule referred to in these Letters Patent and making part of the same.

TO ALL WHOM IT MAY CONCERN: ·

Be it known that I, CHARLES COLBY, of the city of Madison, county of Dane, and State of Wisconsin, have invented certain new and useful Improvements in a Box and Lock for Securing and Supporting the Cords or Band of a Fruit or other Box; and I do hereby declare that the following is a full, clear, and exact description thereof, reference being had to the accompanying drawings, making a part of this specification, and to the letters of reference marked thereon, like letters indicating like parts wherever they occur.

To enable others skilled in the art to construct and use my invention, I will proceed to describe it.

A represents the strip or sheet of material designed to form the sides of the box. This strip is provided with grooves *b e d e f*. The peculiar shape of the grooves *b e* is clearly shown at *g*, Figures 7 and 8, while that of the grooves *d e f* is seen at *h*, Figure 8. The strip A is also provided with slots *i i* and *k*, the object of which will be fully seen hereafter. *m* represents a tuck, formed at the small end of strip A, by means of groove *b*. C represents the bottom of the box, upon which are the projections or rests *n n*. These projections are designed to fit into the slots *i i*, and thus retain the bottom in place.

The manner of putting my box together is as follows: Bend the strip around the bottom, the sides of which must of course correspond to the distance between the grooves, placing the rests *n n* in the slots *i i*, and tuck *m* in slot *k*. The large end of the strip will fit into the recess *x*, seen more fully at Figure 6, while a lock will be formed by a like recess at which the tuck is bent. It may be observed, that by changing the localities of the grooves, yet allowing them to retain the same relative position to each other and the slot *k*, the tuck or loop may be formed at any place on strip A.

What I claim as new, and desire to secure by Letters Patent, is—

1. Fastening and holding the band or cord of the box by means of a single loop, *m*, with double grooves *b e*, which double, forms a hook which keeps the loop in mortise or slot *k*; also the double groove *d e f*, which, when bent, forms a groove to receive and hold the end *e e* of band or strip, substantially as set forth and described.

2. In combination with the subject-matter of the above, I claim the double bearings or rests *n n*, for the bottom of the box, substantially as set forth.

CHARLES COLBY.
